UNITED STATES PATENT OFFICE.

JOHN F. FOLEY, OF ATTLEBORO, MASSACHUSETTS.

DESIGN FOR A HOLDING-CLIP FOR PENS OR PENCILS.

46,727.

Specification for Design.

Patented Dec. 8, 1914.

Application filed September 11, 1914. Serial No. 861,297. Term of patent 7 years.

To all whom it may concern:

Be it known that I, JOHN F. FOLEY, a citizen of the United States, residing at Attleboro, in the county of Bristol and State of Massachusetts, have invented a new, original, and ornamental Design for a Holding-Clip for Pens or Pencils, of which the following is a specification, reference being had to the accompanying drawing, forming part thereof.

The figure is a perspective view of the design, the pen or pencil being indicated in dotted lines.

Copies of this patent may be obtained for five cents each, by addressing the "Commissioner of Patents, Washington, D. C."

The design consists in the formation of the clip, in which a spiral form is utilized to conform with all the mechanical requirements of the clip as shown.

I claim—

The ornamental design for a holding clip for pens or pencils, as shown and described.

JOHN F. FOLEY.
